(57) **CLAIM**

The ornamental design for a fitting for skateboard, as shown and described.

DESCRIPTION

The invention relates to a fitting which is to be attached to the front and/or rear end of a skateboard platform to facilitate the performance of certain maneuvers by a skateboard user.

FIG. 1 is a bottom rear perspective view of a first embodiment of my new design;

FIG. 2 is a top rear perspective view of FIG. 1;

FIG. 3 is a top plan view of FIG. 1;

FIG. 5 is a front elevational view taken in the direction of arrow A in FIG. 3;

FIG. 6 is a rear elevational view taken in the direction of arrow B in FIG. 3;

FIG. 7 is a bottom rear perspective view of a second embodiment of my new design;

FIG. 8 is a bottom plan view of FIG. 7, the top plan view appearing the same as FIG. 3;

FIG. 9 is a front elevational view of FIG. 8; and,

FIG. 10 is a rear elevational view of FIG. 8.
